UNITED STATES PATENT OFFICE.

PAUL NAUMANN, OF DRESDEN, GERMANY, ASSIGNOR TO OTTO & SCHLOSSER, OF MEISSEN, GERMANY.

RAIL-FASTENING.

1,132,962.

Specification of Letters Patent.

Patented Mar. 23, 1915.

Application filed July 23, 1914. Serial No. 852,599.

To all whom it may concern:

Be it known that I, PAUL NAUMANN, a citizen of the Kingdom of Saxony, German Empire, residing in Dresden-A., in the 5 Kingdom of Saxony, in said Empire, have invented certain new and useful Improvements in Rail-Fastenings, of which the following is a specification.

The method of securing rails on two- 10 shoulder sole plates by means of clamping members driven between the base of the rail and the shoulder is already known. It is also known to vary the width of the gage of the rail on the sole plate by exchanging 15 the clamping member for others of different widths.

The novel feature of the present invention consists in the clamping members being guided by webs on their underside in 20 grooves in the sole of the plate in such a manner, that the clamping members will be held even if the base of the rail is not engaged in the recess of the shoulder. The clamping members are then held to the two- 25 shoulder sole plate independently of the rail. Even if there is no rail, they will be held in such a manner that they may be driven out axially to the rail but cannot be tilted off upward nor be levered out. This arrangement 30 has the advantage, that the efficiency of the rail fastening will not be affected by the wear between the base of the rail and the clamping member. When the secure hold of the clamping members depend 35 merely on their grip between the base of the rail and the shoulder, these clamping members must necessarily become slack when a play appears at this point. This is obviated by the present invention.

40 In the accompanying drawings Figure 1 represents a transverse vertical section of one embodiment of this invention. Fig. 2 represents a similar view in which the clamping members are broader, adapting 45 the device to a track of narrower gage. Fig. 3 represents a transverse section in which the clamping members are still broader and adapt the fastener to a track of broader gage than those of Figs. 1 and 2. 50 Fig. 4 represents a plan view of one of said embodiments. Fig. 5 is a section on line 5-5 of Fig. 1. Fig. 6 is an enlarged horizontal section on line 6-6 of Fig. 1, showing the rounded portions of the clamping

member somewhat exaggerated for purpose 55 of illustration.

The soleplate 1 has undercut lugs 2 at its opposite ends, transverse grooves 7 near said ends, preferably underneath the inner vertical faces 20 of said undercut lugs and a plain bearing surface 10 between said transverse grooves adapted to receive the base of the rail 3. The lugs 2 are spaced apart a distance considerably in excess of the width of the base of the rail and said grooves are 65 at a greater distance from each other than the width of the rail base. Two clamping members 4 are interposed between said lugs 2 and the opposite edges of the rail base without contact with the latter. These 70 clamping members are provided on their under sides with ribs 6 and on their upper sides with flanged heads 5. Each of the flanged heads 5 has a vertical bearing face 50 which engages the vertical face 20 of one 75 of the lugs 2, and an overhanging ledge 51 which engages the upper face of the base of the rail near the outer edge thereof and a lip 52 which projects over the lug 2. Each of these clamping members 4 is slightly 80 curved or rounded upward at 4' and the rib 6 thereof is curved or rounded laterally at 6' and has a wedging action in connection with the lug 2 and the adjacent transverse groove 7, whereby the member is wedged between the overhanging undercut lug 2 and the walls of the grooves 7 and held thereby 85 independent of contact with the rail and prevented from tilting outward under vertical stress of the latter. The parts numbered 90 4, 4', 6, 6' and 8 are in one integral piece.

The bodies 4 of the clamping members are of different width as indicated by I, II and III and the ribs 6 on these several forms of clamping members are located at the same 95 distance from the outer edges thereof but at different distances from their inner edges. Such construction renders the clamping members interchangeable in such manner as to permit a change of gage of the railway 100 with the use of the same soleplates and in some instances with the same clamping members. For instance, a narrow clamping member I may be used at the left hand end of the soleplate 1 and a wide clamping member III at the right hand end of said soleplate as shown in Fig. 1 whereby, the rail 3 105 at one side of the track is thrown toward

the left; or said clamping members may be reversed, the plate III being placed at the left and the plate I at the right as shown in Fig. 3, whereby the rail 3 is shifted to its 5 farthest right hand adjustment; or two clamping members II and II of similar widths may be disposed at opposite ends of the soleplate, as shown in Fig. 2, in which case the rail 3 is in position intermediately 10 between the positions shown in Fig. 1 and Fig. 3. These adjustments applied to both rails of the track render this rail fastening adaptable to tracks of widely varying gage.

Preferably the clamping members are 15 made, as seen in Fig. 4, of a shape corresponding to the side of the rail base, over which only the lugs 5 of the clamping members engage in the middle of the sole plate which coincides with the center of the tie. 20 As evident from Figs. 4 and 5 also the middle part of the web may be omitted. Then the two remaining ends are preferably 25 curved in a manner corresponding to the hereinbefore mentioned curvature of the whole web. The lug 5 is provided with an outer lip 52 which projects over the undercut lug 2.

As further evident from Figs. 4 and 5, the web 6 is extended beyond the ends of the 30 clamping members 4 in form of ears 8, which are bent upward, after the clamping members have been driven into their seat, and engage in front of the ends of the lug 2, thereby securing the clamping member on 35 its seat.

I claim:

1. A rail fastening comprising a soleplate having upwardly and inwardly projecting undercut lugs at its opposite ends, transverse grooves in its body below said undercut lugs, and a plain bearing surface between said 40 undercut lugs, said lugs broader than the base of the rail, said lugs provided with ribs on their under faces engaging said grooves, said clamping members having a wedging action independent of the rail between said 45 undercut lugs and said grooves and being provided with heads having ledges projecting over the base of the rail.

2. A rail fastening comprising a soleplate having upwardly and inwardly projecting undercut lugs at its opposite ends, transverse

grooves in its body below said undercut lugs, and a plain bearing surface between said lugs broader than the base of the rail, said 55 undercut lugs having inner vertical faces, clamping members having vertical faces engaging the vertical faces of said undercut lugs and ribs on their under sides adapted to engage said grooves, said clamping members 60 having a wedging action independent of the rail between said vertical faces and said grooves and being provided with heads having ledges projecting over the base of the rail.

3. A rail fastening comprising a soleplate having upwardly and inwardly projecting undercut lugs at its opposite ends, transverse grooves in its body below said undercut lugs, and a plain bearing surface between said 70 lugs broader than the base of the rail, said undercut lugs having inner vertical faces, clamping members having vertical faces engaging the vertical faces of said undercut lugs and ribs on their under sides adapted to 75 engage said grooves, said clamping members having a wedging action independent of the rail between said vertical faces and said grooves and being provided with heads having ledges projecting over the base of the 80 rail and lips projecting over said undercut lugs.

4. A rail fastening comprising a soleplate having upwardly and inwardly projecting undercut lugs at its opposite ends, transverse 85 grooves in its body below said undercut lugs, and a plain bearing surface between said lugs broader than the base of the rail, interchangeable clamping members of different widths provided with ribs on their under faces at different distances from their 90 inner edges and engaging said grooves, said clamping members having a wedging action independent of the rail between said undercut lugs and said grooves and being provided with heads having ledges projecting 95 over the base of the rail.

In testimony that I claim the foregoing as my invention, I have signed my name in presence of two subscribing witnesses.

PAUL NAUMANN.
